UNITED STATES PATENT OFFICE

2,547,558

STEAM GENERATING ELECTRIC IRON

Harry E. Bremer, Milwaukee, Wis.

Application September 22, 1947, Serial No. 775,534

12 Claims. (Cl. 38—77)

1 This invention relates to improvements in steam generating electric irons.

In that type of steam iron wherein the main body portion of the iron serves as a water container and is positioned on top of the sole plate, and wherein there is an electric heating element in the sole plate, steam will continue to flow from the iron at a steady rate as long as there is sufficient water in the container and as long as sufficient heat is being generated by the sole plate heating element. A steady flow of steam, however, is not always desirable, because at certain times less steam may be required and at other times any flow of steam at all may be objectionable.

If steam is flowing continuously from the iron while the latter is standing at rest on its heel it uses up the limited amount of water in the container and makes it necessary to refill more frequently than would be otherwise required. Also, the discharge of unnecessary steam into the room adds to the discomfort of the user. In addition, it is frequently desirable for certain types of work to be able to control the amount of steam discharged or to be able to quickly shift to a dry iron effect.

It is impractical to attempt to control the flow of steam by shutting off electric current or by lowering the thermostat setting because this results in an undesired lowering of the sole plate temperature. It is also impractical to control the amount of steam discharged from this type of iron by means of a shutoff valve as any restriction of the outflow of steam from a closed container is dangerous.

It is a general object of the present invention to provide an improved steam generating electric iron having novel means for quickly and safely controlling the discharge of steam independently of the control for the heating element.

A further object of the invention is to provide a steam iron of the class described which may be used as a dry iron without emptying the water container.

A more specific object of the invention is to provide in an iron as above described means for varying the amount of contact between the bottom of the water container and the sole plate to thereby control the amount of heat transmitted from the sole plate heating element to the water within the water container.

A further object of the invention is to provide in an iron as above described a vertically extending thermostat control rod and a vertically extending steam control rod, there being a compact arrangement whereby said rods may be positioned close to one another without interfering with independent manipulation, and the arrangement also being such as to permit limited tilting movement of the water container relative to the sole

plate without interference from said control rods.

Other objects of the invention are to provide a steam generating electric iron which is efficient in operation, which can be refilled with water while the sole plate is still at maximum heat, which is neat in appearance, and which is otherwise well adapted for the purpose described.

With the above and other objects in view, the invention consists of the improved steam generating electric iron, and all its parts and combinations, as set forth in the claims, and all equivalents thereof.

In the accompanying drawing, illustrating one complete embodiment of the preferred form of the invention, in which the same reference numerals designate the same parts in all of the views:

Fig. 1 is a longitudinal, vertical sectional view through the improved iron, showing the parts in a position for maximum generation of steam;

Fig. 2 is a fragmentary longitudinal, vertical sectional view showing the rear portion of the water container tilted away from the sole plate;

Fig. 3 is a sectional view taken on the line 25 3—3 of Fig. 2;

Fig. 4 is a sectional view taken on the line 4—4 of Fig. 2;

Fig. 5 is a top view of the sole plate in separated condition; and

Fig. 6 is a detail plan view of the thermostat knob.

Referring more particularly to the drawing, the numeral 16 designates a suitable sole plate having a recess 11 in its upper surface near the rear for accommodating a suitable thermostat 12 and having a recess 13 in its lower side near the tip of the iron, the latter recess forming a chamber for steam which is about to be discharged. Any suitable type of heating element may be utilized in conjunction with the sole plate. It is preferred, however, to use a rod type of heating element 14.

One of the ends of this heating element is connected by an electric conductor 15 with one of the terminals 16 of the thermostat 12. The other thermostat terminal 17 is connected by a suitable electric conductor 18 with one of the terminals 19 of the iron. The other terminal 20 of the iron is connected by an electric conductor 21 directly with the other end of the heating element 14.

The terminals 19 and 20 may be constructed for cooperation with a standard socket member connected to the end of an electric cord set and adapted to lead from a source of electricity.

Threaded into the steam discharge chamber 55 13 is a cap 22 having a plurality of steam outlet perforations 23 therein. When properly installed the lower surface of the cap is flush with the lower surface of the sole plate.

The main body of the iron, indicated by the 60 numeral 24, is hollow and forms a container for

water, there being a filling opening 25. The water container has a flat bottom 26, a top wall 27, and a rear wall 28 which is externally recessed as at 29 (see Figs. 1 and 3).

A hollow steam dome member 30 is threaded into an opening 31 in the forward portion of the top wall 27 of the water container. Threaded into another opening 32 in the top wall 27 is a relief valve 33.

Within the water container it is preferred to employ bottom baffles 34, and a substantially horizontally extending upper baffle 35 of a type which is fully described in my issued Patent No. 2,328,124, dated August 31, 1943.

A handle 36 may be suitably connected to the top of the iron by means of a screw 37 extending into the top of the steam dome 30, and by means of a screw 38 threaded into the top wall of the water container. At the rear of the handle and extending inwardly from the upper surface thereof is a control knob recess 39. In addition, the rear of the handle is cut away underneath as at 40 to provide a space 41 above the upper surface of the rear end of the water container.

In order to conduct steam from the chamber 42 of the steam dome to the sole plate, there is a steam discharge tube 43 which has its lower end threaded through the bottom 26 of the water container as at 44 and projecting into a duct 45 leading from the upper surface of the sole plate to the steam discharge chamber 13. Extending upwardly from the steam discharge chamber 13 through a hole 46 and threaded into a thickened portion of the bottom of the water container is a screw 47. The hole 46 is of such size as to provide a slight amount of clearance around the screw for a purpose to be hereinafter referred to.

The present invention contemplates the use of any suitable means for varying the physical relationship between the bottom of the water container and the source of heat so as to control the transfer of heat to the water without controlling the heating element itself. In the preferred embodiment of the invention it is preferred to tilt a portion of the bottom of the water container away from the sole plate to accomplish this purpose and the mechanism which makes this possible will now be described.

By referring to Fig. 1 it will be clear that the upper surface of the sole plate, from approximately the center line of the screw 47 forwardly, is inclined as at 48 so that when the parts are in the position of Fig. 1 there is an angle α formed between the bottom of the water container and the inclined surface 48. This angle is preferably about one degree but has been exaggerated somewhat in Fig. 1 for purposes of clarity.

At the bottom of the recess 29 in the rear of the water container is a horizontal shelf 49 having a rear edge 50 formed with a central recess 51 and with a hole 52 spaced inwardly from said recess (see Fig. 3). A control rod 53 extends upwardly from the thermostat 12 through the hole 52, the said hole being of such size as to provide a small amount of clearance around the rod 53. The upper end of the control rod 53 is slidably and rotatably received in a socket 54 formed in the handle 36. The control rod 53 is equipped with a knob 55 and the latter is positioned in the space 41 so that it can be conveniently manipulated by the fingers when desired.

Referring more particularly to Fig. 6, the knob 55 is preferably formed with a roughened peripheral edge 57 to facilitate manipulation, and is also

formed with an arcuate slot 58 which is concentric with the axis of rotation of the knob.

Projecting upwardly from the upper surface of the sole plate near the rear end thereof is a stud 59 which has its upper end threaded as at 60, the lower end of the stud being rigidly anchored in the sole plate. Threaded on the threaded upper end 60 is the lower end of a control rod 61. Said rod has a lower end collar 62 which engages the lower surface of the shelf 49 and another collar 63 which engages above said shelf. Between said collars is a portion 64 which has substantially less diameter than the external diameters of the collars and which is rotatable within the recess 51 of the shelf. A "fast" threading is used at 60 so that if the rod 61 is rotated $\frac{1}{3}$ of a turn it will produce a raising effect of about $\frac{1}{16}$ of an inch on the rear of the water container due to the engagement of the upper surface of the collar 62 with the lower surface of the shelf 49.

The control rod 61 extends upwardly through the arcuate slot 58 in the knob 55, there being a small amount of clearance between the sides of the slot 58 and the rod. The rod 61 also extends rotatably through a hole 65 in the handle, and its extreme upper end is fitted with a knob 66 which is turnably seated in the handle recess 39. There is a certain amount of looseness in the threaded connection between the lower end of the rod 61 and the upper end of the stud 59. This makes it possible for the rod 61 to be disposed at a slight angle with respect to the stud 59 in certain positions of adjustments of the parts.

In use of the device, and with the container 24 filled with water to a desired level and with the parts in the position of Fig. 1, the electric heating element 14 will transmit heat to the bottom 26 of the water container and to the water therein. Most of this heat will be transmitted efficiently because of the direct contact between upper surface portions of the sole plate and lower surface portions of the water container. The thermostat control knob 55 may be set to maintain a desired sole plate temperature depending upon requirements.

After the water in the water container has reached the boiling point, steam will be generated. This steam will find its way into the steam dome 42 and the pressure in the water container will ultimately force steam outwardly through the tube 43 into the sole plate chamber 13 and out of the steam discharge holes 23. When ironing woolen goods it is usually desirable to have a steady flow of steam. However, it is frequently necessary to set the iron on its heel rest 67 while the work is being straightened out on the ironing board or while the user is otherwise engaged. With the ordinary type of steam iron, steam continues to be discharged at a rapid rate while the iron is on its heel. With the present invention, however, if the knob 66 is turned in a counterclockwise direction to cause partial rotation of the rod 61, this will act through the engagement of the collar 62 with the shelf 49 to tilt the rear of the water container 24 upwardly from the position of Fig. 1 to the position indicated in Fig. 2 so that there is a separation as indicated at b in Fig. 2. This separation is slightly exaggerated in the illustration. Actually a separation of $\frac{1}{16}$ of an inch will suffice. During movement of the parts to the position of Fig. 2 the portion of the bottom of the water container near the tip of the iron rocks down-

wardly from its former position indicated by the line *c* in Fig. 2 to a position in contact with the inclined surface portion 46 of the sole plate. There is enough play in the fit of the screw 47 in the sole plate opening 46 and enough play around the lower end of the steam tube 43 to permit this minor amount of movement. Also, there is enough clearance between the thermostat rod 53 and the hole 52 in the shelf 49 to permit a small amount of raising movement at the rear of the water container while the thermostat control rod 53 remains in fixed position relative to the sole plate. During such tilting there is also a small amount of relative sliding movement between the upper end of the thermostat control rod 53 and the socket 54. In addition, the play in the threading 68 permits a small amount of angular movement of the rod 61 with respect to the stud 59.

As soon as the rear portion of the bottom of the water container is separated from the upper surface of the sole plate as in *b*, there is such a change in the amount of heat transmitted from the heating element 14 in the sole plate to the water container that the discharge of steam from the holes 23 stops almost immediately. Thus, no water is consumed while the iron is at rest on its heel, and no unnecessary steam is discharged into the room. At the same time the thermostat 12 maintains any required sole plate temperature so that the iron is in condition for use whenever desired. Before it is again picked up, if steam is desired, the knob 66 is turned in a clockwise direction to bring the parts back to the position of Fig. 1. This will again cause steam to be emitted from the openings 23.

If, during use of the iron on certain fabrics, only a small amount of steam is desired, then a very fine adjustment of the knob 66 may be made to vary the degree of contact between the water container and the sole plate to whatever extent is desired.

It is apparent from the above that the features of the present invention greatly improve the steam iron and make it possible to quickly control the discharge of steam or the amount of steam discharged independently of the heating element. This not only makes it possible to conserve water and to adapt the iron for use with fabrics requiring less steam, but also makes it possible to instantly convert a steam iron into a dry iron while the container is still filled with water. In other irons of this type which are constructed to be used both with and without steam it is necessary for the water container to be completely emptied if the iron is to be used as a dry iron.

Various changes and modifications may be made without departing from the spirit of the invention, and all of such changes are contemplated as may come within the scope of the claims.

What I claim is:

1. In a steam iron having a sole plate provided with a source of heat therein and having a container for water provided with a bottom positioned over said sole plate, means for tiltably supporting said container on said sole plate, and manually operable means for causing tilting of said container on said tiltable supporting means to vary the heat transfer relationship between at least a portion of the bottom of said water container and said source of heat in the sole plate, and means for conducting steam from said water container to the bottom of said sole plate.

2. In a steam iron, a sole plate provided with a source of heat therein and having a container for water provided with a bottom positioned over said sole plate, and means for conducting steam from said water container to the bottom of said sole plate, means supporting said container for movement of at least a part of its bottom toward and away from the top of the sole plate, and manually operable means for causing said movement to vary the distance between at least a portion of the bottom of said water container and said source of heat.

3. In a steam iron having a sole plate and having a container for water provided with a bottom positioned over said sole plate, a heating element in connection with said sole plate, means for movably supporting at least a portion of the bottom of said water container on said sole plate for selected movement into and out of heat transfer relationship with the upper surface thereof, and means for conducting steam from said water container to the bottom of said sole plate.

4. In a steam iron having a sole plate and having a container for water provided with a bottom positioned over said sole plate, means for conducting steam from said water container to the bottom of said sole plate, a heating element in connection with said sole plate, means movably supporting the bottom of said water container on the top of said sole plate for tilting movement in a vertical plane, and manually operable means for causing said movement.

5. In a steam iron having a sole plate and having a container for water provided with a bottom positioned over said sole plate, a heating element in connection with said sole plate, pivot means connecting an end portion of the bottom of said water container to the corresponding portion of said sole plate, said pivot means providing for a limited amount of tilting movement of the water container in a vertical plane on said pivot means, a readily manipulatable control member spaced from said pivot means for causing said tilting movement, and means for conducting steam from said water container to the bottom of the sole plate and including a conduit portion having a slidable fit in said sole plate.

6. In a steam iron having a sole plate and having a container for water provided with a bottom positioned over said sole plate, a heating element in connection with said sole plate, pivot means connecting an end portion of the bottom of said water container to the corresponding portion of said sole plate, said pivot means providing for a limited amount of tilting movement of the water container in a vertical plane on said pivot means, means for conducting steam from said water container to the bottom of the sole plate and including a conduit portion having a slidable fit in said sole plate, a stud having a threaded upper end projecting upwardly from a point on said sole plate spaced from said pivot means, and a control member rotatably connected to the water container and having a threaded engagement with said stud for causing said tilting movement.

7. In a steam iron having a sole plate and having a main body portion forming a container for water provided with a bottom positioned over said sole plate, a heating element in connection with said sole plate, said sole plate having a steam discharge recess therein, a steam tube for conducting steam through the bottom of the water container into said steam discharge recess 70 of the sole plate, pivot means adjacent said

steam tube connecting the bottom of the water container to said sole plate, said pivot means providing for a limited amount of tilting movement of the water container in a vertical plane on said pivot means, a stud having a threaded upper end projecting upwardly from a point on said sole plate spaced from said pivot means, a control member rotatably connected to said main body portion and having a threaded engagement with said stud, and means for transmitting axial movement from said control member to said water container.

8. In a steam iron having a sole plate and having a main body portion forming a container for water positioned over said sole plate, a heating element in connection with said sole plate, connecting means connecting a part of the bottom of the water container to said sole plate, said connecting means providing for a limited amount of tilting movement of the water container in a vertical plane on said connecting means, a stud having a threaded upper end projecting upwardly from a point on said sole plate spaced from said connecting means, and a control member rotatably connected to said main body portion having a threaded engagement with said stud and having spaced annular shoulders thereon, there being an extension on said main body portion which fits between said spaced annular shoulders whereby axial movement of the control rod is transmitted to said water container.

9. In a steam iron having a sole plate and having a main body portion forming a container for water positioned over said sole plate, a heating element in connection with said sole plate, pivot means connecting a part of the bottom of the water container to said sole plate, said pivot means providing for a limited amount of tilting movement of the water container in a vertical plane on said pivot means, a stud having a threaded upper end projecting upwardly from a point on said sole plate spaced from said pivot means, a thermostat supported on said sole plate for controlling the sole plate heating element, a thermostat control rod projecting upwardly from said thermostat and slidably connected to said water container, a readily manipulatable steam control member for causing tilting movement of said water container on said sole plate, and means for conducting steam from said water container to the bottom of the sole plate and including a conduit portion having a slidable fit in said sole plate.

10. In a steam iron having a sole plate and having a main body portion forming a container for water positioned over said sole plate, a heating element in connection with said sole plate, connecting means connecting a part of the bottom of the water container to said sole plate, said connecting means providing for a limited amount of tilting movement of the water container in a vertical plane on said connecting means, a stud having a threaded upper end projecting upwardly from a point on said sole plate spaced from said connecting means, a thermostat supported on said sole plate for controlling the sole plate heating element, a thermostat control rod projecting upwardly from said thermostat and slidably connected to said water container, a knob on said thermostat control rod having an arcuate slot which is concentric with the axis of rotation of said knob, and a readily manipulatable steam control member for causing tilting movement of said water container on

said sole plate and having a rod portion extending upwardly through said arcuate slot.

11. In a steam iron having a sole plate and having a main body portion forming a container for water provided with a bottom positioned over said sole plate, a handle connected to the top of said water container, there being a horizontal recess between a portion of the rear of the handle and the rear portion of the water container and said water container having an inwardly recessed rear wall below said horizontal recess, a heating element in connection with said sole plate, a connecting member connecting a portion of the bottom of the water container with said sole plate, said connecting member providing for a limited amount of tilting movement of the water container in a vertical plane on said connecting member, a thermostat supported on said sole plate for controlling the sole plate heating element, a thermostat control rod projecting upwardly from said thermostat through the recess formed by the recessed rear wall of the water container, a knob on said thermostat control rod positioned in the horizontal recess beneath the rear handle portion and having an arcuate slot which is concentric with the axis of rotation of said knob, and a readily manipulatable steam control member for causing tilting movement of said water container relative to said sole plate and having a rod portion extending upwardly through said arcuate slot of said knob.

12. In a steam iron having a sole plate and having a main body portion forming a container for water provided with a bottom positioned over said sole plate, a handle connected to the top of said water container, there being a horizontal recess between a portion of the rear of the handle and the rear portion of the water container and said water container having an inwardly recessed rear wall below said horizontal recess, a heating element in connection with said sole plate, a connecting member connecting a portion of the bottom of the water container with said sole plate, said connecting member providing for a limited amount of tilting movement of the water container in a vertical plane on said connecting member, a thermostat supported on said sole plate for controlling the sole plate heating element, a thermostat control rod projecting upwardly from said thermostat through the recess formed by the recessed rear wall of the water container, a knob on said thermostat control rod positioned in the horizontal recess beneath the rear handle portion and having an arcuate slot which is concentric with the axis of rotation of said knob, and a readily manipulatable steam control member for causing tilting movement of said water container relative to said sole plate and having a rod portion extending upwardly through said arcuate slot of said knob and extending rotatably through the rear portion of the handle, and a knob on the upper end of said rod portion.

HARRY E. BREMER.
